UNITED STATES PATENT OFFICE.

ERNST C. ORTMAYER, OF CHATTANOOGA, TENNESSEE.

BED CONSTRUCTION.

Application filed March 4, 1926. Serial No. 92,116.

My invention relates to beds. In my co-pending application Serial Number 739,754 filed September 25, 1924, I have described a bed particularly adapted for use by invalids and patients in hospitals or sanitariums.

One of the objects of my present invention is to provide a bed whereby a bedpan may be placed under a patient and removed therefrom after use without any discomfort or soiling of the bedclothes, and without liability of injury to a patient who may have undergone a serious operation, where to move certain parts of the body would be harmful or even dangerous.

Another object of my invention is to provide means whereby a patient convalescing from a long illness may accustom himself gradually to sitting up, while still resting on the bed, thus obviating the annoyance of having to be propped up with pillows, which are continually getting out of place and causing great discomfort.

Other objects and uses of my invention will become apparent as the description progresses.

The invention will be more fully and easily understood by reference to the accompanying drawings, in which:

Figure 1 is a side elevation of the bed with the parts of the auxiliary frame in normal position and the mattress lowered.

Figure 2 is a plan view on an enlarged scale showing the operation of the head-raising mechanisms.

Figure 3 is a view showing in detail the mechanism for raising and lowering the mattress.

Figure 4 is a view on the line 4—4 of Figure 3.

Referring now to the drawings, 1 denotes the head and 2 the foot of the bed. 3 denotes the angle iron connecting head and foot portions; 4 the bed-spring and 5 the mattress. 6 represents what will be herein-after referred to as the main frame, which is attached to the head and foot pieces by suitable attaching means, such as the brackets 7, 7. These brackets act also as bearings for shafts to be hereinafter described.

Superposed on the main frame 6 is a frame 8 which for convenience in description will be hereinafter termed the auxiliary frame. This auxiliary frame will for further convenience in description be considered as comprising three main sections:—head section 9, central section 10, and leg

and foot sections 11^a, 11^b. The central section 10 is preferably rigidly attached in some suitable manner to the main frame 6, while the head section 9 merely rests thereon, being adapted to swing upwards (as, for example, on pivot 12 by which part 9 is connected to part 10), and thus through any desired angle. It will thus be seen that by the use of this device one can gradually accustom a person who has been confined in bed for some time, to sitting up.

Similarly the parts 11^a and 11^b merely rest on the frame 6 and are adapted to be raised to any desired position to accustom the patient to gradually bending his knees. For this purpose, as in case of the head-piece 9, the part 11^a may be made to swing on the pivot 13 by which said part is connected to the central portion 10. Parts 11^a and 11^b are preferably connected by any mechanism which will effect simultaneous movement of the said parts, as, for example, by mechanism producing a toggle action, as is described in my copending application, mentioned above. Suitable mechanism is indicated on the drawing by the reference character 11^c.

Stretched across the entire auxiliary frame 8 is a sheet of canvas or other suitable material on which the patient lies. This sheet may be provided at 15 with an opening for the convenience of the patient.

Mounted on longitudinal shaft 16, which operates in bearings 23, are worms 17, 17, adapted to gear with worm wheels 18 on shafts 19. Mounted also on the shafts 19 are pinions 20 adapted, as shaft 16 is turned, thus rotating worm 17 and driving worm wheels 18, to mesh with toothed rack 21 and draw the spring and mattress downwardly and away from the frame 6 or upwardly and towards the frame 6 according to the direction in which the wheels and pinions are caused to rotate. Brackets 22 mounted at the head and foot of the bed act as bearings for shafts 16 and 19.

Mounted in brackets 7, 7 and duplicated on each side of the bed is screw shaft 24. On this shaft is mounted, near the head of the bed, sleeve screw 25. Mounted on the sleeve screw is spiral gear 26, which meshes with pinion 27 on longitudinal shaft 28, and at the end of the sleeve screw, between gear 26 and the head of the bed is mounted, on the shaft 24, gear 29 adapted to mesh with pinion 30 on longitudinal shaft 31. Brackets 7 mounted

on the head and foot of the bed act as bearings for the shafts 24, 28 and 31.

Mounted on the frame 6 near the front end of the sleeve screw 25 is roller bearing 32. The base of this bearing may be of wood or metal, and this may have at or near the end of the sleeve screw a right angled abutting extension 33, adapted to act as a thrust bearing for the sleeve screw 25. The roller bearing 32 carries a roller 34 turning on pin 35, the purpose of which will be presently explained.

Mounted on the sleeve screw 25 are trunnion 37 and nut 36, and attached to trunnion 36 is arm 38, which is bent upwards for the latter portion of its length to bear on head piece 9. The arm 38 carries on its abutting end a roller 39.

Attached to the under side of the head-piece 9 is a wedge 40, which I preferably provide with a cavity 41 in which the roller 39 may rest when the head-piece 9 is in raised position, said roller bearing directly on the edge 42 adapted to fit and hold it securely against movement further forward without further rotation of the sleeve-screw 25.

At the foot of the bed, and attached to the end of foot portion 11^b is a bracket 43 slotted at 44 to fit trunnion 45, this latter being adapted when the shaft 24 is turned to move along the screw threads 46 thereon and operate the knee-flexing apparatus.

The operation of my invention is as follows: When the operator desires to lower the mattress he inserts the crank provided onto the end of shaft 16 and turns in a clockwise direction. This rotates shaft 16 with worms 17 thereon, causing the latter to rotate worm-wheels 18 and shafts 19, which in turn rotate the pinions 20, causing them to mesh with the teeth in the racks 21 and move the spring and a mattress downwardly and away from the frame 6. Stops 47 attached to the head and foot of the bed serve to limit the downward movement of the mattress.

To raise the head portion 9, the operator inserts the crank onto the end of shaft 28, and turns in a clockwise direction. This sets up a motion between gears 27 and 26, turning sleeve screw 25 and forcing forward the trunnion 36 carrying the arm 38. The roller 34, as the arm moves forward, rises over the roller 39 and along the lower side of the wedge 40, finding rest in the cavity 41 and bearing directly on the edge 42. Roller 34 also acts as an additional support for the arm when the head piece is in normal position, to prevent breaking of the arm under the strain, with consequent shock and possible injury to the patient or occupant of the bed. In this manner the head piece may be elevated to any desired angle. To lower, the crank is turned in the opposite direction. Roller 34 may, but need not necessarily, perform the function of a support for arm 38

when the head-piece 9 is in raised position.

To bend the knees, the operator inserts the crank onto the shaft 31, and turns in a clockwise direction setting in motion gear 29 and shaft 24 and moving the trunnion 44 along the threaded portion 45 towards the head of the bed. Both the parts 11^a and 11^b are simultaneously moved by the action of the joint 11^c. To lower, the crank is turned in the opposite direction. 75

It is to be understood that I do not limit myself to the specific embodiment of the invention described herein, which is merely for the sake of illustration, as it is obvious that many changes in the details of construction may be made within the scope of the appended claims. 80

I claim as my invention:

1. In a bed for invalids, means to raise a portion adapted to fit the head and trunk of a patient, comprising, a sleeve screw mounted on a shaft and rotatable independently thereof, a trunnion mounted on said sleeve-screw and slidable thereon, said trunnion carrying a bent arm and said arm carrying a roller on its opposite end, means adapted to ensure gradual and gentle movement of the arm over the under side of said head and trunk portion until said portion is raised to the desired angle, and means attached to said head and trunk portion to support said arm when said head portion is in raised position, and assist it in maintaining said head and trunk portion firmly at the angle of elevation at which it has been set until the sleeve screw is operated to change that angle. 100

2. In a bed for invalids, a main frame, and an auxiliary frame, said auxiliary frame comprising a head portion, a central portion and a leg and foot portion, means to raise said head portion comprising, a sleeve-screw mounted on a shaft and rotatable independently thereof, a trunnion mounted on said sleeve screw and slidable thereon, said trunnion carrying a bent arm and said arm carrying at its other end a roller, means mounted on the main frame and means attached to said head portion, both of said means co-operating to effect a gradual and gentle initial movement of the said arm and roller in an upward direction, said gradual and gentle movement being afterwards continued along said means on the head portion alone, until said head portion is raised to the desired position, and means to aid said arm and roller in maintaining said head and trunk portion at the angle of elevation at which it has been set until the sleeve screw is operated to change that angle. 115

3. In a bed for invalids, a main frame and an auxiliary frame, said main frame comprising a head portion, a central portion, and a leg and foot portion, means to raise said head portion comprising a sleeve-screw 130

- mounted on a shaft and rotatable independently thereof, a trunnion mounted on said sleeve screw and slidable thereon, said trunnion carrying a bent arm and said arm carrying at its other end a roller, a roller bearing mounted on the main frame and carrying a roller, and a wedge-shaped element mounted on the under side of the head portion, the roller carried by said bent arm resting against the roller carried by said roller-bearing and against said wedge when the head portion is in flat or normal position.
4. In a bed for invalids, a main frame and an auxiliary frame, said main frame comprising a head portion, a central portion, and a leg and foot portion, means to raise said head portion comprising a sleeve-screw mounted on a shaft and rotatable independently thereof, a trunnion mounted on said sleeve screw and slidable thereon, said trunnion carrying a bent arm and said arm carrying at its other end a roller, a roller bearing mounted on the main frame and carrying a roller, and a wedge-shaped element mounted on the under side of the head portion, said wedge having near one end a cavity adapted to receive the roller on said bent arm and hold it against forward movement, the roller carried by said bent arm resting against the roller carried by said roller-bearing and against said wedge when the head portion is in flat or normal position.
5. In a bed for invalids, a main frame and an auxiliary frame, said main frame comprising a head portion, a central portion, and a leg and foot portion, means to raise said head portion comprising a sleeve-screw mounted on a shaft and rotatable independently thereof, a trunnion mounted on said sleeve screw and slidable thereon, said trunnion carrying a bent arm and said arm carrying at its other end a roller, a roller bearing mounted on the main frame and carrying a roller, and a wedge-shaped element mounted on the under side of the head portion, said wedge having near one end thereof a cavity adapted to receive the roller on said bent arm and hold it against further forward movement, said cavity being rounded at its uppermost part, said rounded portion merging at one end into a straight edge making an angle of approximately 90° with the under side of the head portion.
6. In a bed for invalids, a main frame and an auxiliary frame, said main frame comprising a head portion, a central portion, and a leg and foot portion, means to raise said head portion comprising a sleeve-screw mounted on a shaft and rotatable independently thereof, a trunnion mounted on said
- sleeve screw and slidable thereon, said trunnion carrying a bent arm and said arm carrying at its other end a roller, a roller bearing mounted on the main frame and carrying a roller, and a wedge-shaped element mounted on the under side of the head portion, said wedge having near one end thereof a cavity adapted to receive the roller on said bent arm and hold it against further forward movement, said cavity being rounded at its uppermost part, said rounded portion merging at one end into a straight edge making an angle of approximately 90° with the under side of the head portion.
7. In a bed for invalids, a main frame and an auxiliary frame, said main frame comprising a head portion, a central portion, and a leg and foot portion, means to raise said head portion comprising a sleeve-screw mounted on a shaft and rotatable independently thereof, a trunnion mounted on said sleeve screw and slidable thereon, said trunnion carrying a bent arm and said arm carrying at its other end a roller, a roller bearing mounted on the main frame and carrying a roller, and a wedge-shaped element mounted on the under side of the head portion, the roller carried by said roller bearing co-operating with the wedge-shaped element to give said bent arm and the roller carried thereby a gradual and gentle initial movement when it is desired to raise the head portion.
8. In a bed for invalids, a main frame and an auxiliary frame, said main frame comprising a head portion, a central portion, and a leg and foot portion, means to raise said head portion comprising a sleeve-screw mounted on a shaft and rotatable independently thereof, a trunnion mounted on said sleeve screw and slidable thereon, said trunnion carrying a bent arm and said arm carrying at its other end a roller, a roller bearing mounted on the main frame and carrying a roller, and a wedge-shaped element mounted on the under side of the head portion, the roller carried by said roller bearing co-operating with the wedge-shaped element to give said bent arm and the roller carried thereby a gradual and gentle initial movement when it is desired to raise the head portion, and said wedge-shaped element having near one end thereof a cavity adapted to receive the roller on said bent arm and hold it against further forward movement, said cavity being rounded at its uppermost part, said rounded portion merging at one end into a straight edge making an angle of approximately 90° with the under side of the head portion.

In testimony whereof, I have signed my name to this specification this 23rd day of February, 1926.

ERNST C. ORTMEIER.
